FURNITURE SLIP COVER

Leo Mednick, Philadelphia, Pa., assignor to Lincoln Textile Products Co., Inc., Boston, Mass., a corporation of Massachusetts

Filed Dec. 11, 1961, Ser. No. 158,448
6 Claims. (Cl. 297—224)

This invention relates to a novel improvement in furniture slip covers. More particularly it relates to a stretchable slip cover which can be quickly and easily attached to and detached from a chair or sofa.

The stretchable slip covers of this invention can be used to fit snugly on any one of a number of articles of furniture of the same type, but differing in size or style.

It has been known in the past to provide slip covers which were stretchable and could readily be attached to cover any one of similar articles of furniture. These prior slip covers have generally been made from a knitted fabric. This knitted fabric was used because of its stretching characteristics. However, the knitted fabrics suffered from many disadvantages. They were generally porous in nature and when used in connection with large pieces of furniture it was sometimes possible to see right through the fabric. Furthermore, the knitted fabrics generally were not durable in that they were prone to tearing, stretching and readily wearing out. For the most part a knitted fabric can only stretch easily in one direction and when the fabrics were stretched to too great an extent, they became distorted and did not return to their original shape.

Another problem with the stretchable slip covers previously used was that there was no means of permanently securing a ruffle or skirt to the bottom of the cover prior to the installation of the cover. After placing the cover on the upholstered piece of furniture it then became necessary to sew the skirt to the cover or to apply the skirt by means of metal hooks.

The slip covers of this invention provide a distinct advantage over the so-called "custom-made" slip covers. In the custom-made covers a non-stretchable fabric is cut to the exact size of the upholstered furniture and then is made into a slip cover with a zipper in the back to allow for easy installation. However, a tendency to stretch a custom-made slip cover, as when sitting in the upholstered furniture, would cause the fabric to pull at the seams since the slip cover fabric itself was not stretchable.

In the instant invention, any stretching of the cover caused by sitting is taken up by the stretchability of the cover fabric, and there is no wear on the seams.

It is therefore an object of this invention to provide a novel furniture slip cover.

It is a further object of this invention to provide a slip cover that is relatively non-porous.

It is yet a further object of this invention to provide a slip cover that does not wrinkle in use.

It is a further object of this invention to provide a one-piece slip cover that requires no tacking or metal parts to secure it in place.

It is a further object of this invention to provide a washable slip cover that requires no ironing prior to use.

It is a further object of this invention to provide a slip cover which is readily stretchable in two directions.

It is another object of this invention to provide a novel means for securing a slip cover to a chair.

It is a further object of this invention to provide a novel stretchable cover for the cushion of an upholstered chair or sofa.

In one aspect of this invention these and other objects are accomplished by providing a furniture slip cover comprising a back portion, arm portions, and a seat portion,

2

said furniture slip cover being made from a woven fabric comprising a major portion of non-elastic yarn and a minor portion of elastic thread wrapped with a non-elastic yarn.

5 In another aspect of the invention I provide a furniture slip cover comprising a back portion, arm portions and a seat portion with a skirt secured to the lower perimeter of said slip cover, said skirt having two ends thereof separated in the rear portion of said slip cover, a first 10 pair of tapes secured to said skirt along the junction of said slip cover and said skirt, said first pair of tapes being located on the interior surface of the arm portions of said slip cover, and a second pair of tapes being secured to the junction of said skirt and the rear portion of said slip cover adjacent the open ends of said skirt, said skirt having a plurality of openings along the junction line of said skirt and said rear portion of said slip cover whereby the fit of the slip cover can be adjusted by appropriate tying of said tapes to provide a smooth, wrinkle-free appearance.

15 In yet another aspect of this invention I provide a slip cover for a cushion comprising a stretchable fabric, said slip cover including a top portion, a bottom portion and a side portion which laterally spaces the top and bottom 20 portions, said slip cover being openable at the rear thereof and along a portion of two sides thereof, said bottom portion having an upwardly and inwardly extending lip, and said top portion having a downwardly and inwardly extending lip and being adapted to cover the bottom lip.

25 Other objects and many of the attendant advantages of this invention will be readily appreciated as the same becomes better understood by reference to the following detailed description when considered in connection with the accompanying drawings wherein:

30 FIG. 1 is a perspective view of a chair and cushion having the slip cover of this invention thereon;

FIG. 2 is an exploded view of the flat patterns for the slip cover;

35 FIG. 3 is an exploded perspective view of the slip cover elements partially assembled;

FIG. 4 is a sectional view, partially in phantom and partially in perspective, of the pattern for the slip cover for a cushion;

40 FIG. 5 is a perspective view of the cushion cover prior to the insertion of the cushion;

FIG. 6 is a perspective view of the cushion cover similar to FIG. 5, but with the cushion inside;

FIG. 7 is an enlarged sectional view taken along the line 7—7 of FIG. 6;

45 FIG. 8 is an enlarged fragmentary top plan view of a portion of the fabric embodying this invention;

FIG. 9 is a diagrammatic view illustrating the weave of the fabric;

50 FIG. 10 is an enlarged perspective view of a portion of the elastic thread used in the fabric;

FIG. 11 is a diagrammatic rear elevational view of the slip cover skirt illustrating the tie strings prior to their attachment;

55 FIG. 12 is a diagrammatic rear elevational view of the slip cover skirt illustrating two of the tie strings after attachment;

FIG. 13 is a diagrammatic rear elevational view of the slip cover illustrating the other two tie strings immediately prior to attachment;

60 FIG. 14 is a diagrammatic rear elevational view taken from the inside of the slip cover and illustrating all of the tie strings after attachment;

FIG. 15 is a perspective view of the chair of FIG. 1 taken from the rear thereof, and illustrating the slip cover of this invention after all of the tie strings have been attached;

FIG. 16 is a diagrammatic view illustrating the location of each of the tie strings with respect to the remainder of the slip cover; and

FIG. 17 is a perspective view similar to FIG. 1, but showing another type of chair which may be covered by the slip cover of this invention.

My present invention may be embodied in a slip cover for any type of upholstered furniture such as club chairs, wing chairs, club sofas, sectional sofas and sofa beds.

For ease of illustration, the disclosure will be directed specifically to providing a slip cover for a club chair having a square cushion, as shown generally at 20 in FIG. 1.

The slip cover for this chair is shown generally at 22 in the exploded view of FIG. 3. Slip cover 22 basically comprises a rear portion 24, a back portion 26, a seat portion 28, a front portion 30 and two arm-encasing side portions 32 and 34.

The patterns for forming the various portions of the slip cover are shown in FIG. 2. As seen therein, the rear, back, seat, and front portions are all cut from a unitary piece of fabric.

Rear portion 24 comprises parallel sides 36, outwardly extending tabs 38, tapering sides 40 and a horizontal edge 42. Extending inwardly from approximately the center of edge 42 is a diagonal cut line 44. The purpose of this diagonal cut will be explained hereinafter.

Adjacent rear portion 24 and integral therewith is back portion 26. This portion includes outwardly extending tabs 46 which are adjacent parallel sides 36 of rear portion 24. Sides 48 taper slightly inward from tabs 46. Although tabs 46 are shown as being integral with the remainder of back portion 26, it is possible for ease of manufacture to cut the tabs 46 from a separate piece of fabric and subsequently stitch them to the remainder of back portion 26.

Adjacent back portion 26 and internal therewith is seat portion 28. This portion includes parallel sides 50 which extend to lower edges 52 of the back portion.

Adjacent seat portion 28 and integral therewith is front portion 30. This portion includes outwardly extending tabs 54 and horizontal edge 56. Here again tabs 54 can be cut from a separate piece of fabric and subsequently stitched to the remainder of front portion 30. In this case front portion 30 can be formed as an extension of sides 50 of seat portion 28.

Arm-encasing side portions 32 and 34 are identical in structure, and the description of one applies equally well to the other. As seen in the pattern for side portion 34, each side portion includes upper and lower horizontal edges 60 and 62 respectively. One side includes a downwardly and outwardly extending edge 64, a substantially horizontal edge 66 extending outward from edge 64 and edge 68 extending downwardly and inwardly from edge 66 to the bottom horizontal edge 62. The other side includes a downwardly extending vertical edge 70, an inwardly extending horizontal edge 72 adjacent to edge 70 and a downwardly and outwardly extending edge 74 connecting edge 72 and horizontal bottom edge 62. It is seen that side portion 32 is partially secured to front portion 30 by stitching edge 74 to the outer edge of tab 54 along line 76.

After cutting the fabric to the pattern illustrated in FIG. 2, the three sections of the slip cover are assembled as shown in FIG. 3. The rear portion 24 and back portion 26 are formed into a back encasing shape by stitching the upper and outer edges of tab 46 to the sides 36 along lines 78. The side portions 32 and 34 are formed into an arm encasing shape by stitching edges 70 and 72 to edge 74 along line 80. The slip cover is completed by securing each side portion 32 and 34 to the main body of the slip cover. This is accomplished by stitching edge 74 to the outer edge of tab 54, edge 60 to the upper edge of tab 54, the remainder of edge 60 to side 50, edge 64 to side 48, edge 66 to the lower edge of tab 46 and edge 68

to side 40 and tab 38. These various connections are shown by appropriate arrows in FIG. 3. The connections explained with respect to side portion 32 are identical for side portion 34.

The pattern for the cushion slip cover is illustrated in FIG. 4. The cushion cover basically comprises a top portion 90, a side portion 92 and bottom portion 94. Top portion 90 comprises parallel sides 96, outwardly extending tabs 98 and an upwardly extending tab 100. Each tab 98 includes a horizontal edge 102, an upwardly and outwardly extending edge 104, and an inwardly and upwardly extending edge 106. Tab 100 includes an upper horizontal edge 108 and downwardly and outwardly extending side edges 110 which join with edges 106.

Bottom portion 94 is identical in shape to upper portion 90 and includes parallel sides 112, outwardly extending tabs 114 and downwardly extending tab 116. Each tab 114 includes edges 118, 120 and 122 which correspond to edges 102, 104 and 106 respectively of tabs 98. Downwardly extending tab 116 includes horizontal edge 124 and side edges 126. For the purpose of clarity, the various elements of the tabs have been indicated on the portions which are in phantom in FIG. 4.

Side portion 92 is rectangular in shape and includes upper edge 130, lower edge 132 and side edges 134.

The assembly of the cushion is illustrated in FIGS. 4 and 5. Side portion 92 is secured to upper portion 90 by stitching along the line 136 which connects edge 130 of the side portion to the lower edge of the top portion. Bottom portion 94 is similarly secured to side portion 92 by stitching along line 138. As seen in FIG. 4, bottom portion 94 is formed into a cushion-encasing shape by stitching edges 126 to edges 122 along lines 140. Likewise edges 110 are stitched to edges 106 along lines 142 in upper portion 90. Side portion 92 is then bent into the shape shown in FIG. 5 and stitched at its upper edge 130 to sides 96 of upper portion 90 along line 144. Likewise lower edge 132 of side portion 92 is stitched to sides 112 along lines 146. If desired, piping 148 may be included in all of the seams to provide a decorative effect. Edges 118 of tabs 114 are then stitched to edges 134 along lines 150. Edges 102 are then stitched to edges 154 along lines 152. As seen in FIG. 5, stitched lines 152 slightly overlap stitched lines 150.

The cushion is covered by inserting it in the opening between upper portion 90 and lower portion 94, as seen in FIG. 5. Tab 116 is then wrapped around the rear face of the cushion to completely encase it. The covering is completed by overlapping tabs 114 and 116 with tabs 98 and 100 of the upper portion. It should be noted that due to the angularity of edges 110, 106, 122 and 126 the tabs will all face inwardly when stitched along these edges. This insures a secure fit over the rear edge of the cushion, as seen in FIG. 6.

In FIG. 7 a cushion 160 is shown in its completely covered condition. Note that tabs 116 and 100 completely encase the rear edge of the cushion. Note also that tabs 100 and 116 are hemmed at 162 and 164, respectively.

The fabric from which my slip cover is made is shown generally at 170 in FIG. 9. This fabric is woven and comprises a plurality of strands of relatively non-elastic yarn 172 interwoven with a minor portion of elastic material 174. As seen in FIG. 10, the elastic material comprises a core 176 such as synthetic or natural rubber. This core is a strand which is either exuded or spun from the rubber material and is substantially round in cross section. The core 176 is covered with a winding 178 of a relatively non-elastic textile material, which is usually the same material with which the elastic material is woven.

The non-elastic yarn can be cotton, nylon, rayon, or a polyester, such as Dacron polyester. Cotton is preferred because of its relatively inexpensive cost. A preferred fabric comprises 94% cotton strands and 6% elas-

tic yarn. Thus, there will be approximately one strand of elastic yarn for every 16 strands of non-elastic yarn. Although slight deviations in the relative percentages of the elastic to non-elastic yarn can be made, a 94% to 6% ratio has been found to give the best results. Thus, when too large an amount of elastic yarn is present, the fabric becomes extremely hard as with a rubber band. When too little elastic yarn is present, the fabric will not fit snugly on the furniture being covered and thus will not retain its wrinkle-proof quality.

The fabric is woven with the elastic strands in a stretched condition. Thus, when the fabric is taken from the loom and the elastic strands are released, the fabric will pucker, as illustrated at 180 in FIG. 8. This puckering condition is caused by the contraction of the elastic strands while the non-elastic strands cannot contract.

In one specific embodiment of the fabric, I provide 94% cotton yarn and 6% elastic strands wrapped with cotton yarn. The wrapping can vary between 45 and 75 turns per inch. The fabric has a final percentage stretch of 35% in the warp and 77.5% in the filling. The shrinkage in laundering at 100° F. is 25% in the warp and 5% in the filling. The fabric has good color fastness and may be printed when in a stretched condition.

Using the above specified fabric, the furniture slip covers of this invention provide many distinct advantages. Since the fabric can be made to have a controlled amount of stretching in either direction, a single slip cover can be used to cover any one of many upholstered pieces of furniture snugly. For instance, one slip cover has been found to be able to cover over thirty different styles of square cushioned club chairs. The fabric is never used in its fully stretched condition when used as a cover. Even assuming this limit were reached, it would still become apparent that the woven fabric would be relatively non-porous since in this condition the fabric would substantially appear as a normal woven non-elastic fabric. This provides a distinct advantage over a highly stretched knitted fabric.

Since the elastic yarn will cause the slip cover to cling securely to any given article of furniture, there is no need for ironing these slip covers after washing.

The fabric is cut while in its relaxed condition shown in FIG. 8. As a general rule the fabric should be cut to allow for about 60% expansion in the length throughout the slip cover.

Due to the highly elastic nature of the slip cover, it can be manufactured in one piece and requires no subsequent stitching or hooking to hold it in place. It has also been found that a skirt 200 (FIG. 1) can be permanently 50 stitched to the lower peripheral edges of the unitary slip cover. Thus, the skirt 200 is stitched to edge 42 of the rear portion 24, edges 62 of the side portions 32, 34 and edge 54 of the front portion 30. The skirt 200 is unitary in structure except for an opening adjacent cut 44 in rear portion 24 (FIG. 11). At this opening skirt 200 defines a left flap 202 and a right flap 204. Piping 206 (FIG. 1) may be added along the stitch line of the skirt if desired.

The skirt can be made of any fabric. However, it is preferably made from a non-elastic woven cotton cloth. Since the skirt is not elastic it is applied to the lower peripheral edge of the slip cover by stretching the lower edge prior to stitching the skirt thereto. Thus, the skirt will appear pleated when the slip cover is in its relaxed condition. However, by previously stretching the lower edge, the skirt will accommodate any size chair that can be accommodated by the slip cover. The amount of pleats remaining in the skirt after the slip cover is placed on a chair will depend on the amount of stretching required to apply the slip cover.

As seen in FIG. 11, left flap 202 has tapes 206 and 208 stitched thereto. Similarly, right flap has tapes 210 and 212 stitched thereto. These tapes can be made of any fabric, such as woven cotton. In FIG. 16 a diagrammatic view of a chair 214 is shown having a schematic 75

skirt identical in structure to skirt 200. The purpose of FIG. 16 is to show the exact location of the tapes with respect to the remainder of the slip covers. Thus, as seen in FIG. 16, tape 206 is secured approximately midway back on one arm portion of the chair. Likewise, tape 212 is secured midway back on the other arm portion. Tapes 208 and 210 are secured to the outer edges of left and right flaps 202 and 204, respectively.

Left flap 202 is also provided with a plurality of slots 220, 222 and 224 along the stitch line connecting the flap to rear portion 202. These slots are also shown in the diagrammatic view in FIG. 16.

The chair shown in FIG. 1 is covered by first removing the cushion. The back of the chair is then covered by sliding rear portion 24 and back portion 26 over it. The arms of the chair are then covered by stretching-side portions 32 and 34 over the respective arms. The front portion 30 is then aligned in its proper place and the various seams are straightened out.

The securing of the skirt in place is illustrated in FIGS. 11 to 15. The first step requires pulling tapes 208 and 212 tight so as to give a smooth appearance for the cover and subsequently tying them as at 226. Tape 210 is then inserted through one of the slots 220, 222 or 224 depending on the size of the chair being covered. Tapes 210 and 206 are then pulled tight and secured by a suitable knot, as at 228. It should again be pointed out that FIG. 14 is the view as seen when looking from the inside out on the slip cover. As seen in FIG. 15, when the securing is complete, all of the tapes will virtually disappear and the skirt will give a smooth and neat appearance. The tightening of the tapes will cause the skirt to closely abut the legs of the chair, and thus snugly fit the bottom of the chair.

The purpose of diagonal cut 44 should now be apparent. This cut permits the overlapping of flap 204 on flap 202 and thus permits the insertion of tape 210 in any one of the three slots which are provided. Without the cut 44, this overlapping could not be accomplished while retaining a smooth appearance for the cover.

The inner surfaces of the slip cover are held securely in place by the use of tubes 230 (FIG. 1). These tubes are placed on top of the slip cover and forced into the folds between the arms of the chair and the seat of the chair, and the back of the chair and the seat of the chair. The retainer tubes 230 are sufficiently bulky in cross section to prevent their accidental withdrawal on the normal pull on the back or side portions. The cushion of the chair is then covered in the manner described above and replaced on the chair.

Although this invention has been described with respect to providing a cover for one specific chair, it should be remembered that other chairs of the general type club chair with a square cushion can be covered by the slip cover disclosed. Thus, this same cover could be used on chair 240 shown in FIG. 17. Likewise, by judiciously cutting the patterns, the teachings of this invention can be used in providing slip covers for T-cushioned club chairs, club sofas and other forms of upholstered furniture.

It is thus seen that I have provided a slip cover which is unitary in structure and will fit any number of a particular type of upholstered furniture. The slip cover of my invention requires no metal parts for keeping it in place and requires no stitching subsequent to its application.

Obviously, many modifications and variations of the present invention are possible in the light of the above teachings. It is therefore to be understood that within the scope of the appended claims, the invention may be practiced otherwise than as specifically described.

What is claimed as the invention is:

1. A furniture slip cover comprising a rear portion, a back portion, arm portions and a seat portion with a skirt secured to the lower perimeter of said slip cover,

said skirt having two ends thereof separated in the rear portion of said slip cover, a first pair of tapes secured to said skirt along the junction of said slip cover and said skirt, said first pair of tapes being located on the interior surface on the arm portions of said slip cover, and a second pair of tapes being secured to the junction of said skirt and the rear portion of said slip cover adjacent the open ends of said skirt, said skirt having a plurality of openings along the junction line of said skirt and said rear portion of said slip cover whereby the fit of the slip cover can be adjusted by appropriate tying of said tapes to provide a smooth, wrinkle-free appearance.

2. The slip cover of claim 1 and including a diagonal cut in the rear portion adjacent said open ends of said skirt.

3. A slip cover adapted to fit many sizes and shapes of upholstered furniture comprising a rear portion, a back portion, arm portions and a seat portion, said slip cover being made from a woven fabric comprising a major portion of non-elastic yarn and a minor portion of elastic thread wrapped with a non-elastic yarn woven throughout said non-elastic yarn in both the warp and filling in order to allow said slip cover to stretch a minimum of approximately 35% in both directions, said fabric having been woven with said wrapped elastic thread in a stretched condition whereby said non-elastic yarn forms contracted areas in the slip cover caused by the contraction of said elastic thread, and said wrapped elastic thread is present in an amount small enough to render said slip cover sufficiently soft and flexible to be applied to various sizes and shapes of upholstered furniture, but in an amount large enough to cause said slip cover to fit snugly on the furniture being covered.

4. The slip cover of claim 3 wherein the wrapped non-elastic yarn is the same material as the yarn with which it is interwoven.

5. A furniture slip cover comprising a rear portion, a back portion, arm portions and a seat portion, said slip cover being made from a woven fabric comprising a major portion of non-elastic yarn and a minor portion of elastic thread wrapped with a non-elastic yarn, and including a skirt secured to the lower perimeter of said slip cover, said skirt having two ends thereof separated in the rear portion of said slip cover, a first pair of tapes secured to said skirt along the junction of said slip cover and said skirt, said first pair of tapes being located on the interior surface of the arm portions of said slip cover, and a second pair of tapes being secured to the junction of said skirt and the rear portion of said slip cover adjacent the open ends of said skirt, said skirt having a plurality of openings along the junction line of said skirt and said rear portion of said slip cover whereby the fit of the slip cover can be adjusted by appropriate tying of said tapes to provide a smooth, wrinkle-free appearance.

6. The slip cover of claim 5 wherein said rear portion contains a diagonal cut adjacent the two open ends of the skirt.
